UNITED STATES PATENT OFFICE.

LOUIS STOCKSTROM, OF ST. LOUIS, MISSOURI.

RESERVOIR FOR OIL-STOVES.

1,066,337.

Specification of Letters Patent.

Patented July 1, 1913.

Application filed January 4, 1911. Serial No. 600,801.

To all whom it may concern:

Be it known that I, LOUIS STOCKSTROM, a citizen of the United States, residing at St. Louis, State of Missouri, have invented certain new and useful Improvements in Reservoirs for Oil-Stoves, of which the following is a specification, reference being had therein to the accompanying drawing.

My invention relates to improvements in reservoirs for oil stoves, the primary object of which is to provide a transparent reservoir for oil stoves, and means for supporting it, whereby the amount of oil in the reservoir is always visible to the operator.

This improved reservoir is especially constructed for use in connection with that class of oil stoves in which a predetermined level of oil is maintained requiring an air-tight reservoir and thereby making it impractical to use a float indicator. For this reason reservoirs of this type have not been provided with any indicator by which the operator could determine when the reservoir is empty.

One of the troubles with this class of oil stoves in the hands of the domestic, with which the manufacturers have been confronted for many years, is the burning, charring and destruction of the wick when the oil supply is exhausted, there being no way for the operator to determine that the supply should be replenished. Operation under these conditions destroys the wick to a large extent and if repeated several times will require a new wick. Especially is this true with the short wick type of oil stove here shown, where but a limited adjustment of the wick independent of the wick raiser can be provided. It is also true to a somewhat less extent in respect to what is known to those skilled in the art as "wickless" oil stoves in which the asbestos ring is used. The replacing of the wick or of the asbestos ring is a disagreeable operation and the principal object of this invention is to have constantly visible before the operator in maintained level oil stoves, the level of the oil through the transparent glass reservoir, so that the operator has a constant reminder while around the stove of the oil supply and when it needs replenishing to avoid burning of the wick or asbestos ring when practically dry and its consequent destruction.

In the accompanying drawings: Figure 1 is a side view of an oil stove with my improved reservoir support combined therewith. Fig. 2 is an enlarged perspective view showing the reservoir support, a portion of the reservoir and the valve plug in separated relation.

For the purpose of illustration, I have here shown my improved reservoir in connection with the short wick type of stove, but I wish it understood that it is also intended for use in connection with the well-known "wickless" stove with the same kind of advantage.

Any suitable form of framework 1, is provided and this carries one or more burners 2 having the ordinary wick controlling member 26. An oil supply pipe 3 communicates with the burners and my invention co-operates therewith to maintain the oil at a predetermined level in respect to the burner by the well-known barometric principle.

My improved reservoir comprises a transparent glass receptacle or reservoir 4. The specific type here shown is a vertically disposed reservoir, and surrounding this reservoir and held between ribs or projections 5 is a band 6. This band 6 is provided with a handle 7 at opposite sides for convenient lifting of the reservoir from its support to be filled and to place it in its support after it is filled. Other forms of handles can be used and the handles differently located without departing from the spirit and scope of the generic invention here disclosed. The lower end of this reservoir is decreased in size, as shown at 8 forming a shoulder 24, 90 and this decreased end has permanently attached thereto a metal collar 9, which extends inwardly and has a depending mouth 10 integral therewith. The outer end of this mouth has a removable metal stopper 11, 95 provided with screw-threads 12, by means of which the stopper is removable. This stopper carries a suitable spring actuated valve 14, the spring 15 normally serving to hold the valve on the valve seat 16. The valve 14 is provided with a projecting stem 17, the operation of which will be presently referred to.

My improved reservoir support comprises a bracket 18 having an opening 19, and depending from this bracket 19 is an annular

wall 20 having its lower end contracted as at 21. Depending from this contracted end 21 is a cup-shaped receptacle 22, which has its bottom connected with the end 23 in any suitable manner.

The opening 19 and the depending annular wall 20 is of internal diameter greater than the diameter of the body of the reservoir 4, whereby the lower end of the body 10 of the reservoir is placed within this depending wall and the shoulder 24 of the reservoir rests upon and is supported by the contracted portion 21 of the wall 20. This construction provides a reliable support for the vertically disposed glass reservoir, which prevents it from being accidentally knocked from its support and broken, and provides a reduced receptacle or chamber 22, into which the reduced end of the reservoir and its metal mouth 10 project. When the reservoir is in the position shown in Fig. 1, the valve 14 is unseated by the stem 17, striking the bottom of the receptacle 22. When the reservoir is lifted, the valve is automatically seated by a spring 15 and prevents any oil contained therein from running out. So long as the oil level in the reservoir 4 is above or near the bracket 18 its level can be seen by the operator. To enable the level 30 of the oil in the transparent glass reservoir 4 to be seen when it is appreciably below the bracket 18 the front and end of the wall 20 are each provided with an opening 25 of sufficient size to enable the oil to be seen therethrough and its level determined. Stoves of this type are either provided with supporting legs (not shown) which will support the frame 11 a convenient height for the operator, or if not provided with 40 legs (not shown) are set on a suitable support, which will maintain the stove in a convenient position for the operator. When supported by legs (not shown) or on a proper support, as indicated, the openings 45 25 will be visible to the operator without the inconvenience of stooping to any appreciable extent.

By means of the form of bracket and support here shown, the operator will be visibly 50 and constantly reminded when the level of the oil is below the bracket 18, and the bracket thus becomes an initial or preliminary indicator and warning to the operator that thereafter care must be used in the further use of the stove to prevent destroying the wick by burning it dry. At the same 55 time, there remains sufficient oil in the reservoir below the bracket for operating the stove a limited time thereafter if necessary, 60 and the openings 25 provide a visible means of determining the level of the oil after the preliminary warning afforded by the disappearance of the level of the oil below the bracket 18.

65 It will be noted that the mouth of the glass

reservoir does not directly communicate with the oil conduit or pipe, but communicates with the cup-shaped receptacle 22.

Owing to the fact that commercial kerosene oil used in connection with these stoves 70 is almost colorless, it is necessary to have a large body of oil visible in order to determine conveniently and quickly the level of the oil in the reservoir.

I am aware that attempts have been made 75 to provide oil reservoirs of the maintained level type with indicators by providing a strip of transparent glass or other transparent material in an opening in the wall of the reservoir, and also by attaching to the 80 reservoir a glass tube communicating therewith in the manner of a boiler gage glass.

By means of a transparent reservoir, a large body of the oil is exposed to view at 85 all times, making it quickly and readily apparent to the operator when it needs to be replenished, and which is not subject to the objections heretofore noted.

Having thus described my invention, what I claim and desire to secure by Letters 90 Patent is:

1. The combination with a wick oil burner, of an oil conduit having one end communicating with the burner, an oil receptacle communicating with the other end 95 of the conduit, and a transparent glass reservoir having a contracted lower end entering said receptacle, and a vertical and lateral support carried by the receptacle for the lower end of the reservoir, whereby the 100 transparent reservoir is a combined oil holder and oil indicator for the purpose described.

2. The combination with a wick oil burner, of an oil conduit having one end 105 communicating with the burner, an oil receptacle communicating with the other end of the conduit, a transparent glass reservoir having a contracted lower end entering said receptacle, the upper end of the receptacle 110 forming a vertical and lateral support for the reservoir to hold it upright with the body portion exposed and said upper end of the receptacle having openings to expose the glass reservoir for the purpose described.

3. The combination with a wick oil burner, of an oil conduit having one end communicating with the burner, an oil receptacle communicating with the other end of the conduit and extending upward and flared outwardly and upwardly forming a lateral and vertical support, said receptacle above the outwardly flared portion having openings, a transparent glass reservoir having a contracted lower end entering the oil receptacle and supported by the lateral and vertical portions thereof, whereby the glass reservoir can be seen approximately throughout its entire length, substantially as shown and described.

4. The combination with a wick oil burner of an oil receptacle communicating with the burner and extending upward and flared outwardly and upwardly forming a 5 lateral and vertical support, said receptacle above the outwardly flared portion leaving openings surrounding the same, a transparent glass reservoir leaving a contracted lower end entering the oil receptacle and 10 supported by the lateral and vertical por-

tions thereof, whereby the glass reservoir can be seen approximately throughout its entire length from any point around the same for the purpose described.

In testimony whereof I hereunto affix my 15 signature in the presence of two witnesses.

LOUIS STOCKSTROM.
